UNITED STATES PATENT OFFICE

137,435

DESIGN FOR A BOW COMPASS

Alexander P. Bartusch, Lockport, N. Y.

Application April 9, 1943, Serial No. 109,938

Term of patent 14 years

To all whom it may concern:

Be it known that I, Alexander P. Bartusch, a citizen of the United States, residing at Lockport, in the county of Niagara and State of New York, have invented a new, original, and ornamental Design for Bow Compass, of which the following is a specification, reference being had to the accompanying drawing, forming part thereof.

Figure 1 is a front elevational view of the bow compass embodying my new design. Figure 2 is a side elevational view of the same. Figure 3

is a front elevational view of the compass on a reduced scale and with the stylus points omitted for convenience of illustration.

My design for a bow compass is characterized by its specific configuration and placement of the adjustment screw approximately midway of the legs, the inner sides of said legs being shaped as shown in Figures 1 and 3.

I claim:

The ornamental design for a bow compass, as shown and described.

ALEXANDER P. BARTUSCH.
